FUEL BURNING METHOD

Milton A. Powers, Detroit, Mich., assignor, by
mesne assignments, to The Timken Silent Au-
tomatic Company, Detroit, Mich., a corporation
of Michigan

Application June 9, 1934, Serial No. 729,928

3 Claims. (Cl. 158—117.5)

This invention relates to novel and improved methods and apparatus for burning liquid fuel in accordance with what has come to be known recently as the "wall flame" principle.

5 This application is a continuation in part of my copending application Serial No. 620,373, filed July 1st, 1932 for Ignition and combustion ring; and of my applications Serial Number 380,527 filed July 24, 1929, now Patent Number 1,888,693 of November 22, 1932, and Serial No. 675,341, filed 10 June 12, 1933.

15 The principal objects of this invention are to provide a new and improved method of fuel projection and combustion, and to develop preferred suitable burner constructions and arrangements for carrying out said method with maximum efficiency.

20 Prior to this invention, liquid fuel burners have been devised for centrifugally distributing oil from a rotating head and throwing it toward a peripheral impingement wall. In some instances attempts have been made to ignite the fuel at a peripheral ring and maintain the combustion there, so as to operate on the desirable and so-called 25 wall flame principle. A burner of this general type is shown for example, in the patent to Forrest A. Heath, No. 1,886,875.

25 In all of such prior devices, however, the oil is atomized by the head and thrown in a very fine and at least partially carbureted spray. In some 30 of these prior devices, the fine spray forms a layer which is intended to be partially separated from the primary air that is supplied by the head for support of combustion. In still others of these 35 prior devices the finely atomized oil is intimately mixed with the air supply directly in or immediately adjacent, the burner head, and high velocity is relied upon to hold the flame toward the periphery. Where oil and air are distributed in 40 slightly separated layers, as well as where the air and atomized oil is intimately mixed in or near the burner head, difficulty of so-called "flash 45 back" has been experienced. This is due to either the continuous or occasional presence of a combustible or even explosive mixture in a zone of the 50 chamber between the peripheral wall and the distributor head. If the velocity of the air draft in such devices becomes lower than the rate of flame propagation from the combustion zone toward the burner head, the flame will follow the mixed 55 atomized oil and air back into the burner head thereby introducing severe strains in the head, and causing carbon to collect on the head and interfere with future operation of the burner. This condition also may be caused by inefficient com-

bustion at the periphery due to unsatisfactory combustion ring design, and when flashback occurs it in turn further upsets and reduces the efficiency of the peripheral combustion. This undesirable condition is also due in great part to 5 improper correlation of the distributing head and the peripheral combustion wall, even though one or the other may in itself be of an efficient design.

10 Accordingly, it is a major object of this invention to teach a novel method and to provide novel oil burning apparatus, all based on the wall flame principle, wherein flashback is completely eliminated without any sacrifice in efficiency of combustion at the flame wall—and, in fact, with 15 greatly increased efficiency of combustion, and of heat distribution and transfer.

More specifically it is an object to provide a 20 liquid fuel burning apparatus which will permit combustion only at the outer periphery of the hearth and adjacent the lower edge of the water leg of the boiler in such manner that heat is 25 efficiently developed and is concentrated and rapidly transferred at the most effective points.

It is another object to provide a liquid fuel 25 burning method in which liquid fuel is thrown from a distributor head in an unatomized condition and without admixture with any appreciable air, and in which there is a substantial intermediate zone between the combustion zone and the 30 distributor in which the unatomized liquid fuel and air streams are actually bodily separated to prevent combustion in said intermediate zone.

Another highly important object resides in the 35 combination of a flame wall designed to efficiently mix and burn oil and air that are supplied to it in distinct layers, and a rotary oil and air distributor that will discharge oil in unatomized and non-carbureted condition while simultaneously flinging it in the same unatomized and non- 40 carbureted condition into shattering impact with a predetermined portion of said flame wall.

It is also a major object to provide, in combination with a flame wall having an upper oil impact portion and a lower air deflecting portion, 45 a compact rotary head comprising a fan for impelling a blast of air toward said deflecting portion and an oil flinging conduit having its discharge end within the confines of said fan and yet arranged to expel the oil without atomization 50 and without admixture with the blast of air prior to impingement on the impact portion of the wall.

A further object is to provide a distributing 55 head arranged close to the hearth and having inclined unrestricted oil tubes adapted to throw

the liquid fuel out toward a flame wall in large droplets in a curved trajectory thus permitting the successful use of a substantially horizontal hearth.

- 5 It is a further major object to devise a special wall flame method of combustion brought about by locating a thin refractory combustion ring substantially inwardly from the boiler wall, throwing a stream of unatomized oil against said ring to shatter and vaporize the oil and simultaneously directing a blast of air against said ring to cause a hot flame to be produced and concentrated above and behind said ring to maintain the latter at a high temperature and to efficiently transfer heat to the adjacent part of the boiler wall. In this connection it is an object to provide a somewhat sheltered ignition and fuel collecting zone within said thin combustion ring, whereby normal combustion can be rapidly attained and efficiently maintained.

It is also an object to provide metal materials for satisfactory use in various parts of an oil burning apparatus.

Another object is to provide a light metallic combustion wall of special design for a liquid fuel burner of the wall flame type, and especially to devise an arrangement in which a metal wall may be most efficiently utilized both in normal operation and when starting and stopping the apparatus.

A further object is to provide an improved flame grill arrangement for liquid fuel burning furnaces of the wall flame type.

A still further object is to provide a metallic hearth for oil burners and an improved fan especially adapted to be used in conjunction therewith.

Further objects are to provide a metal hearth of low cost, for assembly by relatively untrained workers into a boiler unit that will operate with a maximum of efficiency; and to provide a molded or ceramic hearth of low cost which may readily be assembled into combustion chambers of existing coal burning furnaces to operate with a maximum of efficiency.

The foregoing and further objects will fully appear upon a study of the following detailed description when taken in conjunction with the accompanying drawings.

50 Referring now to the drawings wherein like numerals are employed to designate like parts wherever they occur.

Figure 1 is a vertical sectional view taken substantially along line 1—1 in Figure 2, through a coal burning furnace, showing the apparatus of my invention with all its related parts applied thereto.

Figure 2 is a cross sectional view taken on the line 2—2 through the boiler of Figure 1, and showing the distributor, hearth, igniters, combustion ring and flame grillwork in top plan.

Figure 3 is an enlarged fragmentary sectional view taken on line 3—3 in Figure 2, and showing the manner in which sections of a combustion ring are positioned on the hearth, the flame grillwork being omitted for the sake of clarity.

Figure 4 is a fragmentary perspective view in partial section of a pair of ring segments and their connector, corresponding with the form seen in Figures 1—3.

Figure 5 is a perspective plan view of one of the flame grills seen in Figures 1 and 2.

Figure 6 is a fragmentary sectional view similar to Figure 1 but disclosing a different boiler

and a modified type of hearth and combustion ring construction.

Figure 7 is an enlarged fragmentary perspective view, in radial section somewhat as in Figure 3, of the peripheral ring, hearth and boiler leg 5 of Figure 6.

Figure 8 is an enlarged fragmentary sectional view of the burner and hearth construction of Figure 1, with the combustion ring and grillwork somewhat diagrammatically illustrated; and with 10 the method of fuel and air distribution, and the combustion conditions, schematically indicated.

Figure 9 is a sectional view similar to Figure 8, but illustrating details of the modified hearth structure of Figures 6 and 7. This view is provided chiefly for the purpose of illustrating a modified fan, and for showing combustion conditions where no grillwork is utilized.

The preferred burner system in its entirety consists of a distributor unit centrally located in a 20 hearth, and which centrifugally throws oil and air in separate layers to the outer periphery of the hearth; a combustion ring provided adjacent said outer periphery; means for electrically igniting the oil, which is mixed with the air, at 25 the combustion ring; and grills for spreading the flame obtained. There are two forms of this general apparatus for embodiment of the invention. The first is for use in boilers which are specifically designed to take an oil burner, and the 30 second is for use in boilers or furnaces originally designed for burning coal or similar fuels. The first form is referred to as the metal hearth type and the second form as the molded or ceramic hearth type. The reason for the two forms is 35 that in boilers specifically designed to take the burner it is possible to make the hearth of an assembly of metal stampings. Obviously, it would be impractical to attempt to make such stampings for the varied sizes and contours of coal 40 burning furnaces already in use throughout the country.

The furnace of Figures 1 and 2 is of the coal burning type and comprises a boiler 11 supported on a base 15 which forms an ash pit below the 45 grate bars. The bars of course have been removed in the process of converting the furnace into an oil burner, and have been replaced by the following oil burning equipment.

The distributing unit A of Figures 1 and 2 (also 50 see Figure 8) comprises a motor M supported by vertically adjustable legs 1 through an annular frame assembly 2; a distributor head 3 driven by the motor and arranged on top thereof, and into which oil is fed by means of a pipe line 5; and a 55 set of radial finger tubes 6, preferably four in number, and disposed, equally spaced, at the outer periphery of said distributor head and so positioned as to centrifugally discharge the oil radially outwardly. The quantity of oil flowing through 60 pipe line 5 is controlled by suitable valve adjustments (not shown). The air for combustion is drawn through a conical shutter assembly 8 which may be manually adjusted and locked in position to permit the proper amount 65 of air inflow, and thence is projected radially by a metal fan 9 which is attached to and rotates with the distributor head. This fan is stamped into inverted dish shape, with blades 10 struck out angularly at its 70 periphery to provide a circular series of vertical air impelling members, the series being interrupted adjacent each finger tube by removal of a blade to prevent interference with the oil streams by either the blades or the projected blast of air. 75

The oil tube and fan blade relationship further is such that the oil is distributed at a level higher than the center of the air stream. Some of these details are better shown in Figures 6 and 8, and, except for a few important features later to be discussed, this distributor unit is precisely the same as that fully described and illustrated in United States Letters Patent No. 1,882,694, granted to Herbert W. Alden and Milton A. Powers on October 18, 1932. The corresponding mechanism of the modified head of Figure 9 differs chiefly from that of Figures 1 and 2 in a single important detail, later described.

Slightly below the level of the fan and above the top of the supporting legs of the burner head, a horizontal flange 12 is formed on the frame proper to support the inner edges of two semi-circular metal plates 13. Lying upon and extending beyond the outer periphery of said plates there is provided a hearth support plate 14, the outer portion of which may rest on suitable projections of the boiler, such for example as the grate lugs or inwardly projecting portions of the base 15. On top of these hearth support plates, 13 and 14, is molded a hearth 16 which extends radially from the frame assembly 2 to the wall of the combustion chamber of the furnace, thus effectively sealing said chamber against the entry of air other than that which is admitted through the fan 9. The top surface of the hearth 16 is usually flat and horizontal, although in some cases, particularly on very large hearths, it may be desirable to compensate for the drop in the oil stream due to gravity, by a slight downward slope of the hearth away from the burner.

At two diametrically opposite points in the hearth are molded the igniters 18, each of which consists of a central conductor electrode 19, an inner insulating member 20 and an outer insulating member 21. On top of the central conductor 19 is attached a spark point member 22. For further description of these igniters and the ignition system, reference may be had to my copending application Serial Number 731,562, filed June 20, 1934.

In the typical conversion burner installation shown in Figure 1, a control stand C is installed outside of the boiler. The burner, its surrounding parts, and the necessary ignition transformer and associated equipment such as the illustrated electrical conduits, are installed within the compartment formed by the boiler base, which in this instance is the furnace ash pit. Oil flows by gravity to the control stand, being supplied from the usual constant level float chamber at the inside storage tank or, if an outside supply is provided, the oil flows from a conventional wall pumping device with its attached reservoir on the wall above the burner level.

The control stand C, mounted outside of the boiler proper on the usual installation, consists principally of a carrier for the motor condenser, the terminal block for electrical connections, the snap switch for controlling the power to the burner, and a magnetic oil valve assembly of the type disclosed in my pending application Serial Number 448,131, filed April 28th, 1930. The ignition transformer T has high tension leads, as shown, to the igniters in the hearth rim. The transformer is arranged to be clamped rigidly to one of the supporting legs 1.

A variation of this control assembly is made in the case of boiler burner units equipped with metal hearths and adapted for use in furnaces

that are especially designed to burn oil. In such cases, for the sake of compactness, all of the above mentioned parts, with the exception of the snap switch, are assembled as a single unit and installed in a lower compartment below the boiler with rigid attachment by bolting to an edge of the boiler base 15a (as in Figures 6 and 9).

The motor M operates at a speed of approximately 1750 R. P. M. and is of the condenser type. This speed is sufficiently slow to insure long life, and the very low fan load imposed upon the burner during operation assures satisfactory operation throughout its life. Considerable trouble has been encountered in the past with motors, largely due to the failure of the electrical starting switches. Such switches depended upon centrifugal force for operation and due to the very limited space available and their consequent small size could not be made reliable. In addition they were particularly susceptible to failure as the result of over lubrication of the motor, flooding the switch and causing failure. The use of the condenser type motor with the condenser permanently in the circuit eliminates all switches and provides a most satisfactory motor for this application.

Placed around the outer periphery of the hearth 16, but spaced inwardly from the furnace wall, is a series of metal segments 25 clamped end to end to form a continuous combustion ring as shown in Figure 2, and substantially as disclosed in my aforementioned copending application, Serial Number 620,373. Whether the shape is circular, oval or rectangular will depend upon the shape of the combustion chamber into which the unit is emplaced, metal segments of varied curvature as well as straight, being available as required. Moreover, the ring can be made in one piece, either endless or of a single band with its ends abutted or overlapt, and such one-piece design is especially suitable where the chamber is substantially circular in cross section.

Referring now to Figures 3 and 4, each segment 25 has a trough or gutter 27, an oil impact wall or flange 28 extending upwardly from the outer portion of said gutter and an air-directing flange 29 sloping downwardly from the inner portion of said gutter portion and having its marginal portion abutting the hearth 16.

The segments 25 preferably are made of sheet metal of very high thermal conductivity such as heat-resistant chrome steel of comparatively thin section. The segments 25 are connected end to end by means of connectors or clamps 31 which when the ring is not formed in one continuous piece, serve to position the segments in the form of a substantially smooth, continuous ring.

The connectors 31 are formed of thin sheet metal of high heat conductivity and each is made in two pieces. One piece comprises a strip 32 having essentially the contour of the segment 25 and having at its upper edge two ears 33 adapted to fold over and retentively engage the abutted ends of the impact portions 28 of a pair of segments; and two ears 34 at its lower edge adapted to fold over and retentively engage the abutted ends of the flanges 29 of said pair of segments. The other piece, immediately in back of said piece 32, comprises a vertical supporting portion 36, the plane of which is at right angles to the piece 32; and flaps 37 and 38 respectively, at its upper and lower edges, bent to engage the upper and lower portions of the piece 32. This engagement is made permanent by spot welding or other suitable means. At the base of piece 36 is a horizontal

flange 40 at right angles thereto, adapted to rest upon the hearth 16. Struck downwardly from said flange 40 is a finger 41 which is adapted for insertion into the hearth 16 to thereby anchor 5 the segments in their proper location. The outer portions of members 31 are shaped to act as spacers to maintain, during installation, the desired combustion space between the boiler wall and the upstanding impact walls 28 of the seg- 10 ments.

In view of the necessity of installing hearths in heating plants of a wide variety of sizes and shapes segments 25 are available in several degrees of longitudinal curvature as well as in 15 straight pieces. Experience indicates that curved segments shaped to three selected radii of curvature are ordinarily sufficient to allow installation in the normal range of hearth diameters. However, this is only true if the practice in Figure 2 20 is followed, wherein the ends of the lower edge 29 of the segment are cut off at an angle as at 42, rather than radially as is the rest of the segment edge. The space between the corresponding lower edges of the two adjoining segments 25 provides for a reasonable range of play in adjusting the series of segments to fit hearth curvatures other than those corresponding exactly to the curvature of the segments themselves. However, oil or air is prevented from leaking through 30 any opening, that might be formed thereby, by the overlapping wall of the connector piece 32, which is made wide enough to close any possible opening. A further precaution against oil leakage may be taken by inserting an asbestos strip 35 43, of the same width as the connector piece 32, between the latter and the metal segments.

The invention preferably is carried out by placing, on top of the impact wall 28 of the burner ring, a series of light metal grills 45, which pref- 40 erably are made of sheet metal having a high heat resistance and also high thermal conductivity. The grill proper (see Figure 5) is formed from a flat sheet of metal by certain cutting and folding steps; and it comprises a rectangular box- 45 like structure 47 the ends of which are produced by bending the edges of the blank upwardly. The box is open at the top and has a series of lateral openings 48 extending from side to side of the box. The openings are formed by making a series 50 of I-shaped cuts in the base of the box and then folding the metal upwardly from the base, in this manner simultaneously forming a series of trans- 55 verse troughs 49.

At each end of the box 47 are grill supports 50 55 of substantially inverted U shape, the top portions thereof being rigidly secured by spot welding or other suitable means to the lower portion of the box. In the forward leg of each support 50, a finger 51 is struck laterally to provide a notch 60 or saddle adapted to fit the top of the impact wall of the segments 25. The rear leg is plain and is adapted to abut the back of the gutter 27 of said segments. The last-mentioned leg is adapted to be adjustably bent to obtain the proper angle of setting of the grill with respect to the flame ring for maximum efficiency of combustion. This general type of grill, together with its support 50 and broad phases of operation, is 65 the invention of John A. Wilson, who has pending, an application Serial No. 682,374, filed July 27, 1933. The primary purpose of the grillwork will appear later.

Referring now to Figures 6 and 9,—which illustrate, except for slight detailed differences 70 in the head structure of these two figures, a

preferred furnace construction built de novo with a metallic hearth,— the hearth structure comprises a supporting base plate 60 which is bolted at its outer edge to a flange 61 on the boiler base 15a. A central opening in plate 60 is provided 5 into which the distributing head frame fits, and the head is adapted to be bolted to this plate. In view of the support provided by base plate 60 the legs,—such as legs 1 of Figure 1 that are usually provided for conversion burners,— are 10 dispensed with. Their absence results in an increased space below the hearth to provide a large compartment for installation of the burner, control box, ignition transformer, oil valve, etc.

Immediately on top of the plate 60, and between it and the flange 61, is a disc of heat insulating material 63, perforated at its center to fit over the distributor head. Placed around the head and spaced therefrom but resting on the upper surface of insulator 63 and supporting 20 plate 60 and secured thereto by means of cap screws 64, is a series of substantially U-shaped supports 65, horizontally flanged at the upper portions of their legs to support a metal hearth plate 67. Said hearth plate is perforated at its 25 center portion and has an upturned lip 68 to fit a shoulder provided therefor on the distributor head frame just below the level of the fan. In Figure 6, this shoulder is formed on the integral frame 2, but in Figure 9, the framework is of a 30 modified two-part construction, 2a, 12a, with the shoulders produced by striking out a series of tongues 66 from the part 2a.

At the outer edge of hearth plate 67 is a continuous upturned peripheral wall 70 which gives 35 strength to the plate and which is also designed to prevent any unburned oil from flowing down onto the insulator. The wall of the water leg 72 of the boiler B2 is so formed as to have a continuous annular depending portion 73 over- 40 hanging the wall 70 so that all of the unburned oil on the inner surface of said water leg will drip onto the hearth plate 67.

The opening through which the distributor proper projects into the combustion chamber,— 45 and all other openings in the hearth plate 67, including those for the igniters 18,—, are provided with upturned flanges whereby any oil collection on the surface of the hearth plate will be retained and in time vaporized and disposed of in 50 the combustion rather than by draining downwardly into the lower portions to accumulate and cause trouble.

There are two diametrically opposite perforations with upturned lips 89 in the hearth 67 for 55 the insertion of igniters 18. Said igniters are secured in place and their vertical positions fixed by means of clamps 76 which are carried by the plate 60.

Upon the surface of the hearth, and close to 60 the periphery of the hearth plate 67, there is placed a combustion ring 78 which may either be made of a single strip or pressed formation of sheet steel or be constructed from a plurality of segments similar to the segments 25 described 65 above for use in the first form of the apparatus. As aforesaid, a single continuous ring can readily be used in furnaces that are designed de novo to burn oil, and this is particularly true of any installation where a substantially circular ring is permissible.

Although as just stated a non-segmental ring 78 may be utilized, Figure 7 is added to the drawings to illustrate a novel method of constructing the ring in segmental form.

Still referring to Figure 7, the differences between the metal segments 75a and those previously described are: that segments 75a have lower flanges 78 which are lipped at the bottom portion to rest upon the hearth plate 67 and to be rigidly secured thereto, as by means of spot welding; and that the sides of the lower flanges 78 are made to register exactly with the adjacent segments, thus avoiding any V-shaped openings. The reason for this is that in this case the segments are designed for this one boiler and are not used anywhere else. Therefore they can be precisely designed. It is preferable to have considerable slope on the lower flanges of the segments so that the air flowing against them will not be too abruptly deflected. An abrupt deflection would result in a considerable loss in the kinetic energy of the moving air, thus depriving it of a portion of the necessary force required for thoroughly carbureting the vapors at this point to produce efficient combustion.

A one-piece supporting and connecting member 80 is provided at the joined ends of each pair of segments. Its central seat portion 81 is formed to the contour of the segments and it has lateral or wing portions 82 forming vertical supporting legs which have feet 83 designed to be spot welded to the hearth plate 67, thus maintaining the connector in the correct location. Inserted between each member 80 and the segments 75a is an asbestos strip 85, similar to the strip 43 described above with the exception that it can not extend in back of the impact wall 28 because the member 80 is spot welded to the said wall 28.

Preferably, a series of grills 45, as described above, will be placed on top of the impact wall 28.

The fan 9a, shown in Figure 9, has been specially developed for use with the metal hearth in boiler burner units of integral design where certain undesirable characteristics of operation may be inherent unless some special feature, such as this modified fan, is incorporated to prevent their occurrence. This will be explained later.

The modified fan is quite similar, in general construction and operating characteristics, to that already described. It has special blades 87 riveted or spot welded to the top plate portion of the dish-shaped fan structure. The peripheral portion of the fan housing extends downwardly only part way towards the hearth, and terminates in an annular horizontal flange 88, below which are disposed the effective impelling portions 10a of the blades. The flinger tubes 6 extend between the upper portions of the blades and have their tips disposed close to and in alignment with apertures 89 in the peripheral wall of the housing, and hence the oil is discharged above the level of the effective portions 10a of the fan blades, and in complete separation from the air stream. A fan of this type, having long effective blade portions 10a at a considerable distance from the center of rotation and pointed more or less radially, is conducive to imparting a high velocity to the air stream with a minimum of recirculation of the burned gases. The air is directed horizontally outward in a very thin concentrated stream in close proximity to the hearth surface.

The chief or essential features of operation of both forms of my invention are substantially identical. The oil enters the burner as best seen in Figures 8 and 9, through the oil feed tube 5, and is discharged downwardly and outwardly to the inside surface of a revolving distributor head 75 cup 80. The oil upon striking the inner edge of

the revolving cup assumes rotation with the surface of the cup, thus inducing an outwardly directed centrifugal force, which force causes a film of oil from the cup to rise upwardly to the outer edge of the cup where it divides and enters the four outwardly projecting internally smooth flinger tubes 6 in equal amounts for discharge radially without restriction and without atomization or nebulization. The oil that is thus thrown outwardly from the rotary distributor head 3, 10 travels separately from the air stream and strikes the impact wall 28 above the gutter 27, ignition and combustion initially taking place in said gutter, and the flame gradually lifting to the top of the burner ring when normal combustion conditions are obtained. 15

For the purpose of clearly illustrating the operating conditions in Figures 8 and 9, distinctive lines have been added to indicate the paths of the oil and air streams and the manner in which the vapor is formed and burned. A table of legends, disposed above Figures 8 and 9, explains the adopted system.

While four flinger tubes are shown it is possible to reduce this number to two and successful tests have been made using but a single tube for discharging the oil. There is only a minor objection to using a single tube and this results from the fact that the combustion sound has superimposed upon it a swishing overtone produced by the rapidly revolving point of impingement of the single stream of oil against the hearth rim. Combustion otherwise is very good and efficient operation results.

The general method and the modes of operation should be substantially clear from the foregoing discussions and detailed description. There are, however, certain phases and features of the methods and apparatus of the present invention which are highly important and which deserve special emphasis and further consideration as follows:

Oil distribution

The purpose of the wall flame burner and its peripheral igniters is to inaugurate and complete combustion in close proximity to the boiler wall and at a distance from the distributing mechanism. Any tendency for the flame to burn toward the distributing head or in the head would seriously interfere with the remaining combustion at the wall of the boiler to thereby reduce the efficiency of heat transfer to the boiler wall. It furthermore introduces severe strains in the head, and any combustion near the head would cause carbon collection on the distributor and interference with continued operation thereof. I am familiar with the methods, described and used by previous inventors such for example as disclosed in Heath Patent #1,707,474 dated April 2, 1929; Laughlin Patent #1,635,016 dated January 3, 1928; Braun Patent Reissue #17,991 dated March 10, 1931; and Meikle Patent #1,856,720 dated May 3, 1932. In every one of these patents a method of distributing the oil from the head in a finely atomized condition is clearly disclosed, although at least one of the patentees apparently recognized the desirability of maintaining the combustion zone entirely at the periphery. In every case the patented devices embody a rotating distributor head for discharging atomized oil and the necessary air for burning this atomized oil. One of the prerequisites of rapid combustion is the mixing of liquid fuel particles of minute size with air for their combustion, and although this

is exactly what occurs in each one of the distributing mechanisms described in the above mentioned patents, it occurs either all or part of the time in the region at or closely adjacent the head. This quick atomization is either brought about intentionally or necessarily follows from the nature of the oil discharge means or from the relationship of the latter to the air blast. Consequently, difficulty always has been encountered in the past with so called "flash back" of the flame from the wall of the boiler toward the distributing mechanism and in some cases into said distributing mechanism with fatal results.

15 In contrast, my distributing mechanism flings the oil from the ends of the distributor tubes in an unatomized condition, my purpose being to place an even layer of wet unatomized oil around the periphery of the fire rim. To accomplish this purpose the oil reaches the flinger tubes 6 in fairly large droplets and travels in the same state freely to the outer periphery. Examination of the construction as seen enlarged in Figures 8 and 9, will disclose the fact that the tubes are internally smooth and that there is absolutely no obstruction imposed to the force flinging the unatomized oil through the tubes and from their ends in the form of large drops. Moreover, the tube discharge tips are disposed close to the fan outlet periphery, and adjacent the upper level of the latter, so that the oil droplets cannot be atomized, nebulized or carbureted by impact with the fan blades or by action of the air stream. The oil is projected at an angle to the horizontal, and the air stream hugs the hearth.

With particular reference to the flinger tubes 6 on the distributor heads of Figures 8 and 9 they extend radially but are inclined slightly upwardly toward their outer ends. It will be apparent that any oil flowing from distributor tubes, so inclined, will have an upward component as well as an outward one introduced by centrifugal force. The outward component, of course, is very large and results in a very rapid movement of the oil from the tip of the distributor tube through the intervening space to the impingement face of the metal segment. The upward component referred to above is relatively slight in comparison to the outward force but is sufficient to slightly raise the trajectory of the oil. Consequently, as indicated by the arc of the oil travel in Figures 8 and 9 the oil moves upward for a distance before assuming a horizontal direction and then bends downward in its travel to the point of impingement. It will be evident that this downward motion is due to the effect of gravity and that if the end of the distributor tube 6 were horizontal instead of being inclined upward the oil flow would start out in a horizontal direction, and then would soon bend downward. In moving horizontally some of the oil might be whipped into a fine mist by the outgoing air blast, followed by admixture of the fuel mist with sufficient air to support combustion and cause "flash back". In bending quickly downwardly from horizontal tubes some of the oil would fall below the impact wall of the segment ring and even on the hearth, if the latter happened to be of large diameter. Therefore the practice of installing the hearth has been much simplified by inclination of the tube ends to permit the use of a perfectly flat hearth, which is much easier to install than a hearth inclined either upwardly or downwardly or requiring seg-

ments set at levels other than in normal relation to the hearth proper.

The conditions encountered by a drop of oil from the time it leaves the distributor head until it impinges against the hearth rim 28 are as follows. It leaves the tip of the distributor tube 6 at a speed roughly equal to the velocity of the tip, and speeds toward the segment at an angle which is the resultant of centrifugal force and the direction of movement of the tip of the tube. 10 The radial distance from the tube to the hearth in the average size boiler, say 24 inches in diameter, will be about 7 $\frac{1}{2}$ inches. This figure is obtained by subtracting from the boiler radius of 12 inches, the 1 $\frac{1}{2}$ inches inward spacing of the 15 segment from the wall and the tip radius of 3 $\frac{1}{2}$ inches from the center of rotation. This distance will be increased roughly to 10 inches by the diagonal angle of travel of the oil.

The motor speed is about 1750 R. P. M. with 20 the tip turning with a radius of 3 $\frac{1}{2}$ inches which gives it a calculated velocity of 573 inches per second. As the distance is 10 inches the time elapsed will be .017 second or roughly 2 hundredths of a second. The time interval is therefore much too small to allow more than a superficial effect upon the relatively large oil droplets as they travel across the intervening space. That this is true is easily demonstrated by listening to the "patter" of the oil particles as they 30 strike the impact wall of the metal segment. This sound is frequently outstandingly noticeable among the combustion noises and is always easily discerned. If the oil were atomized finely in or adjacent the head, the air friction would 35 slow down the speed of the minute particles, more time would elapse and the heat would more rapidly vaporize the greatly reduced bulk of the particle. It has been this very condition which caused so much trouble on earlier designs with 40 the attempts to use the head as an atomizer, instead of limiting its functions to that of a distributor for large oil particles. As previously stated, some of the subject matter of the present application, comprising broadly the method of 45 flinging concentrated streams of oil in large droplets against an impact wall, is disclosed in my earlier case, Patent Number 1,888,693. However, through later improvements, I am able to practice substantially the same method without 50 extending the flinger tubes upwardly through the fan housing where they are subjected to temperatures that reduce the size of the projected droplets; and to practice the general method with 55 greater efficiency through addition of a heat concentration step adjacent the impact wall, whereby larger drops can be readily vaporized completely.

The oil particles projected in accordance with my improved method are ten or more times 60 heavier than the atomized spray particles of earlier methods, and are several times larger in diameter. Viewed with a stroboscope, the concentrated stream of oil from each tube is $\frac{1}{16}$ inch or more in diameter, depending upon the oil volume being consumed per unit of time; and many of the droplets spatter to a diameter of $\frac{1}{8}$ inch or more against the impact wall, forming a definite wet ring or narrow band around the impact wall. This wet band of course vanishes instant- 70 ly (i. e., as fast as it is formed), when the burner is in normal operation.

Air flow

The air for combustion is supplied at a pre- 75

determined velocity and fixed rate by the fan, and the method of directing the air into and from the fan, the course it follows across the hearth as well as the method of mixing it with the oil vapors at the hearth rim during combustion are highly important. As mentioned previously all air for combustion—(except in the case of very high oil rates when auxiliary air is supplied, for details see Powers U. S. Patent 10 #1,909,007 issued May 16, 1933)—is supplied through the fan, the amount being controlled by the manually set and locked air shutter 8 within the frame of the head. The air shutter, as will be seen in referring to Figure 8 and as can be ascertained by reference to the previously mentioned Patent #1,882,694, consists of a conical nest of two overlapping plates with several large openings in each. With a maximum air flow setting the two sets of openings coincide, while 20 adjustment in reducing the air flow may be made by relatively oscillating the two plates to reduce the overlapt area of the ports. This air shutter even when closed to a minimum setting, is arranged to allow some air to enter in accord with 25 Underwriters' Laboratories requirements which consider such minimum air supply desirable to minimize the hazards of operation in case the air supply is accidentally closed.

The fan used generally on the typical molded or ceramic hearth installation as shown in Figures 1 and 8, consists essentially of a shallow sheet metal cup into the rim of which has been stamped a multiplicity of fan blades. The number and size of the blades 10 are varied for different sizes of hearth constructions. In general a small hearth will require the use of a fan having a large number of small blades while a large hearth will operate better with a fan having fewer and farther projecting blades. Tests 40 have shown that the latter type fan does not have a much greater actual capacity than the small fan with more blades. However, the air is thrown from the revolving head of the long blade type at a greatly increased velocity which 45 allows effective mixing with the vapors at a greater distance as for example, in a long or large diameter hearth where the shorter blade type would be quite ineffective as the air velocity at the hearth rim would be too low to insure 50 proper mixing and poor combustion would ensue. Conversely a fan of the long blade type would create altogether too much turbulence and air velocity if installed in a small hearth, even if the air shutter were materially closed. Experience 55 then has dictated a series of fan sizes, approximately six in number which when properly selected will produce the optimum results in any hearth size within the limits of burner capacity.

An interesting and important characteristic of the air stream is indicated in Figures 8 and 9. In all cases the air flow is directed downward toward the hearth surface. Even though the largest portion of the air in a given case as determined by test may flow from the upper 65 portion of the fan blades, as in Figure 8, yet this air very rapidly seeks the level of the hearth and flows outward in close proximity to its surface. For example the air leaving the upper portion of the fan 9 may be traced and found 70 to converge in a thin outwardly moving stratum at the hearth surface. In some cases the air stream may assume this position within a very few inches of the edge of the fan. When the region of the air-stream is probed by a high tension arc across a portable gap, it is possible 75

to visually determine the velocity, direction, and general activity of the air surrounding the extended arc streamer. This method has the advantages of convenience, sensitivity, and as the arc has no weight, instantaneous responsiveness 5 to air changes without introduction of interference to the free flow of the air. With this method the airstream from the fan is found to be concentrated at a thickness of say, $\frac{1}{2}$ inch—four inches distant from the fan, as indicated in 10 Figures 8 and 9. From this point on it continues to maintain practically the same velocity until it reaches the deflecting "toe" (29 in Figure 8, 18 in Figure 9) of the metal combustion-producing ring, decreasing in thickness to compensate for the rapidly increasing area it covers in spreading outward. Immediately above the airstream will be found a sharply defined area 15 of relative quiet. The airstream is deflected upward upon reaching the inclined toe of the metal segments, but this deflection is made without absorbing more than a small portion of the energy of motion, and the airstream discharges upwardly and outwardly at the angle imparted to it by the inclined surface. Consequently most 20 of it strikes the upper edge of the oil impingement wall as indicated in Figures 8 and 9 and relatively little enters the protected confines of the intermediate ignition trough 27.

30

COMBUSTION

1. Burner ring and location thereof

Both air and oil travel has now been traced to the vicinity of the upper edge of the impact 35 wall of the segment—the air flowing over the edge and the relatively large oil droplets impinging at some level below this same edge. Detailed consideration of a preferred electrical ignition means and method are considered in a companion application about to be filed, and as far as this discussion is concerned ignition will be considered as having been accomplished and a cold flame burning above the surface of oil collected in the gutter 27. A definite period 40 elapses in the starting of a burner in a cold boiler 45 between the time ignition is completed, with the flame propagated entirely around the periphery of the hearth rim, and the time when sufficient heat has been released to maintain the normal 50 heat balance that occurs after the fire has been 55 burning for some time. As explained later, the elapsed time when using the chrome metal hearth segments is much shorter than when the old style clay segments were installed.

With ignition completed and all of the parts substantially at atmospheric temperature, due to the comparatively small amount of heat released initially but a small portion of the oil is being vaporized. Such vapor accumulates principally 60 in the gutter 27 below the oil impingement line. In view of the limited quantity of vapor, air is also present in the gutter and hence combustion occurs in said gutter. This concentrated heat release, inside the segment, rapidly heats the 65 segment wall; more oil is vaporized; and the flame enlarges in size, a portion still remaining in the ignition groove but an increasing amount of flame appearing above the segment and behind the impingement wall. Shortly the rate of vapor release is so high and the amount in the groove 70 so large that the flame entirely leaves the groove and rises to the region above and behind the segment as indicated by lines representing flame in Figures 8 and 9. When this occurs,—generally within only a minute after ignition is completed— 75

all of the oil is vaporized immediately upon impingement. Ordinarily there will be no appreciable accumulation of oil in the groove upon starting, but if for any reason such as delay in ignition or poor oil, a small amount collects it is rapidly vaporized. Normal operating conditions therefore follow within a short time after starting, with the segments sufficiently hot to vaporize all of the oil received, with the proper amount of air supplied for complete burning of that oil, and with combustion initiated and completed principally in the space behind and above the segments.

The highly heated metal surfaces against which the oil strikes are of great advantage because the force of the impact has a definite shattering effect upon the oil drops which effect, in conjunction with their intimate contact with the hot surface, causes instantaneous and complete vaporization. A relatively small amount of heat is required to vaporize oil in comparison, for example with water. Approximately 100 B. t. u. is absorbed by a pound of oil during vaporization in contrast with almost ten times as much for a pound of water. Consequently the cooling effect upon the thin hot segments is not as pronounced as might be expected. However care should be taken to differentiate between the amount of heat required as compared with the intensity of that heat. The distinct advantages of the chrome steel over the old ceramic tile lie both in the increased amount of heat transmitted to the oil and, of still more importance, the heat intensity (temperature) of the impinging surface, which factors will be discussed in detail later.

Referring to Figure 9 wherein are indicated combustion and flame conditions where there is no grillwork, the air flows over the top edge of the metal ring 75 while oil is being vaporized just below that edge. Part of the vapor fills the ignition trough 27 and as there is but little air for combustion in the groove, no visible combustion occurs in the groove. Neither is there any combustion along the inside edge of the impact wall 28 due to the very rapid flow of air and vapor past that wall. However as the two pass over the top edge there is a marked rolling and mixing effect somewhat in the manner of the eddy pools in the lee of a sharp bend in a river bed. The space between the ring 75 and the bottom of the boiler wall is thus a protected space containing actively mixing air and vapor. The resultant combustion, partly visible and partly difficult to discern due to its bluish transparency, results in a large evolution of heat part of which is used to heat the ring and to vaporize the continuing oil supply, and a large amount of which is transmitted through the adjoining boiler wall back of the ring where maximum efficiency of heat transfer to the boiler water is obtainable. While for giving the most perfect results obtainable there is a certain distance between the segment wall and the boiler wall for any given condition of flame setting it is preferred to make this distance approximately 1½ to 2 inches. However it may be widened materially or shortened somewhat. It is not desirable to decrease the space to less than 1 inch as it then becomes too limited to be effective in mixing or to trap sufficient combustible mixture to thoroughly heat the ring and the boiler wall.

2. Grillwork arrangement

However, only a portion of the total combustion occurs to the rear of the segment, a large

part of it continuing as the rapidly moving gases roll upward. When large quantities of oil are supplied at rapid rates there is a marked tendency for the flame to become tall and relatively thin in section, as indicated by arrows in Figure 9. At times the flame will be undesirably long so as to extend upwardly from and out of the combustion chamber. To overcome this as well as to produce other desired results the previously described grill members 45 are preferably used with results as indicated by the arrows in Figure 8. The grillwork serves to further mix the gases, and speed the ensuing combustion above the grills, resulting in a much shorter, bushier flame and allowing more oil to be burned in a given combustion space. Other advantages such as a more stable flame, quicker heating during starting, and better quality combustion are obtained. The more stable flame, with very efficient combustion, is in great part due to the arrangement of the grills substantially at right angles to the direction of air flow along the surfaces of the sloping deflector portions of the combustion ring, and to the provision of the troughs 49. The combustible gases thus flow at relatively high velocity through the transverse passages 48 adjacent the troughs and create a vacuum effect in the latter which tends to draw the gases into the troughs and in this manner hold the flame down. The grills preferably overhang the large annular chamber,—formed by the boiler leg, the hearth and the rear surface of the combustion ring,—, and thus increase the eddying effect and flame concentration within the said chamber.

MATERIALS

35

1. Comparison metal and ceramic impact walls

Prior to my proposed use of the metal combustion ring and commercial adoption of the same, refractory clay segments were installed and cemented in place against the boiler wall. These old segments had the same inner contour as the metal segments but occupied all of the space that is provided now between my metal segments and the boiler wall. The flame burned above the clay segments and most of the heat for the vaporization of the oil necessarily had to be transmitted through the ceramic material which is inherently a heat insulator. The use of a metal segment allows combustion to occur immediately back of the segment, from which point the heat is freely transmitted in large quantities through the thin metal wall to the oil impingement surface. Heat is dissipated from the impingement surface with great speed. Much higher operating temperatures are thus obtained enabling poorer grades of oil with higher boiling point fractions to be burned efficiently. Another most important advantage is the quick heating of the metal segment without any real accumulation of oil in the ignition groove during the starting period in a cold boiler, and the instantaneous, complete vaporization of all oil, even in very large drops, thereafter. The slow heating of the old type resulted in accumulation of oil with improper combustion during the starting period, and also to an undesirable extent during subsequent operation, not to mention the gradual collection of the heavy ends of the oil during intermittent operation for short periods such as occurs during the summer when the installation is arranged to function for heating the domestic water supply.

Such difficulties are entirely eliminated with the metal ring design, which preferably is com-

posed of 16-18% chrome steel, but which may embody lower percentages of chromium, with very low carbon content. In addition there are important savings in manufacture, transportation and installation, as a result of the increased ease of manufacture, light weight, easy packing, freedom from breakage, and ease of installation.

2. Comparison metal and ceramic hearths

10 In making a molded or ceramic hearth according to this invention, a sheet metal pan is supported as previously described after carefully cutting to fit the outline of the boiler chamber. Over this is molded the flat bed of wet, air-drying, clay 15 refractory, at the periphery of which is installed the metal fire rim made up of a series of metal segments with interlocking connectors anchored in the hearth bed. After hardening, a bed is obtained that is rugged and permanent, free from 20 air leaks, a good insulator preventing excess heat loss to the chamber beneath, and a permanent anchorage for the metal fire rim.

The described metal hearth shown in Figures 25 6 and 9 has the advantage of being a factory built assembly accurately fitting the boiler for which it was specially designed and capable of being installed in that boiler by relatively unskilled workmen in a minimum of time. The materials used 30 are capable of withstanding the most severe conditions to which they may be subjected without failure. Heat transmission downward is reduced by the asbestos insulator, while the necessary expansion of the metal parts upon change in temperature is provided for by the use of the flexible 35 bracket supports, with relatively free suspension of the parts most severely exposed. The metal selected for the hearth plate preferably is 16 to 18 percent chrome steel with characteristics similar to those described for the segments above.

40 The characteristics of operation, of the burner assembly in which a metal hearth is incorporated, are quite similar to those discussed for the refractory hearth. However, unless some special provision is made to eliminate it, the very undesirable characteristic of "panting" is frequently 45 encountered where metal hearths are installed. This condition is present in certain installations and makes itself known by a throbbing sound of varying rapidity and often of severe intensity 50 which can be heard all over the house and which seriously interferes with proper combustion. Many theories have been advanced to explain the 55 phenomenon and probably the most nearly correct is that the combustion chamber, flues, smoke pipe and possibly the chimney act as an open-end organ pipe through which air waves are readily transmitted. Such waves travel back and forth at a rapid rate affecting the combustion each time 60 in a cumulative manner, thus tending to accentuate the condition rather than to reduce it. Opening the fire door, a flue door, putting holes through the hearth or making any similar opening, even though slight, usually stops the condition 65 instantly. The least troublesome installations in the field in this respect are the old and quite poorly assembled boilers which leak air. A tight boiler and hearth is almost certain to be susceptible to "panting" and this condition is usually immediately encountered on the perfectly 70 tight boiler assembly into which the metal hearth is built. I have discovered that a fan, of the design shown in Figure 8, with its more positive and concentrated air output, is capable of remedying the difficulty without requiring the usual 75 provision of special air leaks.

3. Fan material

In view of the relatively high fan temperatures resulting from contact with the highly heated gases, a material capable of withstand- 5 ing such action is desirable. It is found that ordinary sheet steel will warp and disintegrate in time under these conditions. Stainless steel having an analysis of 18% chromium and 8% nickel has been used with success on many thou- 10 sands of installations. However, I have found by thorough test that an equally practical fan may be made from 4 to 6% chromium steel of very low carbon content (less than .1%). Such fans, now in use on about 10,000 installations, 15 have an excellent record; and while the material is subject to slight surface oxidation (during the idle summer layover period in a moist basement), the change is one of appearance only and is not of any material consequence. The 20 chromium has a stabilizing influence, as to resistance to heat that would cause other materials to disintegrate, and also as to warping—the new material being surprisingly free from any tendency towards distortion or buckling under the 25 heat. This is in part due to the low carbon content specified for the steel to insure a free working material under the dies—a material which takes its shape with a minimum of springiness and with freedom from inherent internal 30 stresses which commonly causes a change in shape later under the heat of actual operation. This quality is of particular importance as fabrication of these parts in the past has been greatly complicated by the inability of the dies to han- 35 dle the material due to variation in hardness and the rapid tendency to work-harden and become brittle during the forming operations. The above formula produces a fan easy to build, with long life and freedom from warpage in use. 40

The invention may be embodied in other specific forms without departing from the spirit or essential characteristics thereof. The present embodiments are therefore to be considered in all respects as illustrative and not restrictive, the 45 scope of the invention being indicated by the appended claims rather than by the foregoing description, and all changes which come within the meaning and range of equivalency of the claims are therefore intended to be embraced 50 therein.

What is claimed and desired to be secured by United States Letters Patent is:

1. A method of combustion consisting of the steps of projecting liquid fuel toward a hot va- 55 porizing surface in the form of large unatomized droplets, without appreciable admixture with air, and with sufficient velocity to carry them into impingement with said surface; and supplying air for combustion into intersection with the projected droplets only in the zone of impingement and vaporization of the liquid droplets on said surface.

2. A method of combustion comprising the steps of flinging a concentrated stream of un- 65 atomized fuel droplets from a liquid fuel source toward a hot vaporizing surface that is relatively remote from said fuel source and separated therefrom by an intermediate zone of fuel travel; and supplying air to support combustion in such 70 manner that substantially no air is mixed with said droplets in the intermediate zone but that air is mixed with the fuel solely in the region of vaporization of the latter at said hot surface, whereby combustion is maintained at all times 75

only adjacent the area of intersection of the fuel droplets with the hot wall.

3. A method of combustion comprising the steps of throwing liquid fuel in the form of large unatomized droplets toward an impingement surface, supplying heat at said surface to vaporize part of said liquid fuel, directing air for combustion against said surface to thoroughly mix

with the vaporized fuel, igniting the air and fuel mixture and utilizing part of the heat of combustion to raise said surface to a temperature sufficient to completely and instantaneously vaporize all of the large unatomized droplets that impinge upon said surface after combustion is initiated. 5
